UNITED STATES PATENT OFFICE.

ALLSEY OSCAR BROWNE, OF LOUISVILLE, KENTUCKY.

GAME.

SPECIFICATION forming part of Letters Patent No. 630,485, dated August 8, 1899.

Application filed November 11, 1898. Serial No. 696,153. (No model.)

To all whom it may concern:

Be it known that I, ALLSEY OSCAR BROWNE, a citizen of the United States, residing at Louisville, in the county of Jefferson and State 5 of Kentucky, have made a new and useful Invention in Games, of which the following is a specification.

My invention has for its object the production of a game which two or more persons may 10 play and in such manner that by properly combining in rows or lines movable parts, such as dominoes or dice having definite numbers or indications affixed to them, individual scores may be effected and a total number of 15 points scored, the first of the players to score such total number being the winner of the game.

The invention will be fully understood by referring to the accompanying drawings, in 20 which—

Figure 1 is a perspective view of the board upon which the game is played, one of the movable parts—to wit, double blank—being illustrated on the board in dotted lines in the 25 lower left-hand corner thereof; and Fig. 2 is a perspective view of the same movable part removed or detached from the board.

The board B, as illustrated, is constructed by cutting or otherwise producing a series of 30 parallel grooves in a board of the proper length and width in such manner as to leave definite spacing-strips S, S', S², to S⁷, inclusive, the two lower strips S⁶ and S⁷ being of substantially the same length as the board itself, and 35 the remaining strips S⁵, S⁴, S³, S², S', and S relatively shorter, as shown. In the spaces between the strips are painted, printed, or otherwise affixed illustrations of the dominoes, dice, or movable parts used in playing 40 the game, the parts, when dominoes are used, being arranged preferably in the following order. On the lower line, between the strips S⁶ and S⁷, the double blank, blank-six, blank-five, blank-four, blank-three, blank-two, and 45 blank-one in succession; between the strips S⁵ and S⁶ the double six, double five, double four, double three, double two, and double one; between the strips S⁴ and S⁵ the six-five, five-four, four-three, three-two, and two- 50 one; between the strips S³ and S⁴ the six-four, five-three, four-two, and three-one; between the strips S² and S³ the six-three, five-

two, and four-one; between the strips S' and S² the six-two and five-one, and between the strips S and S' the six-one. Upon the six-one, 55 between the strips S and S', is placed the numeral "5." Upon the blank-one, between the strips S⁶ and S⁷, is placed the numeral "10." Upon the double blank, between the strips S⁶ and S⁷, are placed the numerals "15" and 60 "20." At the left of the grooves, between the several strips S' to S⁶, inclusive, are placed the numerals "15," "20," "30," "35," and "40." At the bottom of the vertical lines of dominoes are placed from left to right the 65 numerals "20," "25," "30," "35," "30," and "30." At the extreme left of all of the strips, in a line parallel with the hypotenuse of the triangle made by the left-hand ends of the strips S to S⁶, inclusive, is placed the numeral 70 "40."

The numerals "5," "10," and "15" in the several corners of the triangle, made by the strips S to S⁷, inclusive, are arbitrary, while the numerals at the extreme left of the ends 75 of the several rows of dominoes indicate in multiples of five the summation of the spots upon the several rows of dominoes between said strips. To illustrate, "15," the number at the left of the row between the strips S' 80 and S², illustrates the nearest multiple of five of the summation of the spots upon the two dominoes six-two and five-one, the number "20" illustrating in like manner the summation of spots on the dominoes between the 85 strips S² and S³, &c., the number "20" at the extreme left of the row of dominoes between the strips S⁶ and S⁷ illustrating the summation of the spots upon the dominoes in that line. In like manner the vertical summation of the spots in the extreme right-hand line is "30," in the next adjacent line to the left "30," in the next adjacent line to the left of that line "35," in the next to the left "30," in the next to the left "25," and in the 90 last or extreme left-hand vertical line "20."

The number "40" in the line parallel with the hypotenuse of the triangle is an arbitrary number, such that when added to all of the numbers indicated upon the face of the board 100 the total summation will amount to "400," which is the arbitrary name I have chosen to give to my novel game.

The game is played, preferably, as follows:

All of the dominoes are placed in the box lid or cover or upon a table face down and well shuffled. It may be played by two or more persons. If two play, each draws fourteen dominoes. If three play, each draws nine dominoes, in which event a single domino will be left over. This domino should be placed upon the smooth part of the board with the spots up, so as to be played in its regular place when the game has progressed far enough. If four play, each draws seven dominoes. If five play, each draws five dominoes, and the three dominoes left over should be placed spots up upon the smooth part of the board, to be played each at the very first opportunity. If six play, each draws four dominoes and the four remaining dominoes should be placed spots up upon the smooth part of the board, to be played each at the very first opportunity. If seven play, each draws four dominoes, &c. Suppose now four persons to be playing the game. Each therefore draws seven dominoes. In order to start the game, the person having the double blank must play first in the lower left-hand corner, and he who plays this domino scores fifteen, putting the domino in position face up, as shown in dotted lines, Fig. 1, of the drawings, the same domino being illustrated in full lines in perspective view Fig. 2. It is now the turn of the player next to the left of the one who first played. This player has three opportunities to play—to wit, six-blank, the domino which should be placed adjacent to double blank, or blank-one in the lower right-hand corner, which counts ten, or six-one in the upper right-hand corner, which counts five. Suppose blank-one to be played in the lower right-hand corner. Then the next player to the left has four possible plays—to wit, blank-six adjacent to the double blank, or two-blank to the left of blank-one, or double one above blank-one, or six-one in the upper right-hand corner, &c. Should he play six-one, he scores "5." In like manner the game proceeds, a play being only possible after the three arbitrary dominoes—double blank, blank-one, and six-one—have been played, as already indicated, by placing the proper domino adjacent to the right or left or above or below, as the case may be, in such manner as to proceed toward the completion of either a horizontal or vertical line in the proper sequence.

It will often happen that a player may have several dominoes that could be played, and it is then at his option to elect which he shall play. Of course the player's judgment should dictate the best play, or if he has but one domino which can be played that must be played regardless of the consequence. The only chance for a player to make a count except in the three corners wherein five, ten, or fifteen is scored is effected by completing one of the several horizontal or vertical lines. It will be apparent, therefore, that each player must direct his efforts to the completion of

such line or lines as will make the greatest total score. He must not, however, for any reason withhold a domino with which he hopes to complete a line later. If that be the only domino in his hand which can be played at that time, the play must be made and the opportunity for finishing the line left to another.

Since the lines of the triangle intersect or cross each other, it will be often possible to finish two lines and not infrequently three lines by playing a single domino. For example, suppose that the second line or line of doubles needs only the double three to complete it, it should be remembered that a line can be completed anywhere, in the middle as well as at either end. Suppose that the ninth line, which crosses the second line at this point, needs only the double three also for its completion. It is apparent, therefore, that the player who plays the double three in position at this time will complete the two lines—namely, the second horizontal and the ninth vertical line—thereby making a score of "35" 90 and "40," or "75."

It will be obvious that various combinations of the dominoes may be made if the above order of play is followed and that much good judgment as to the proper play will be necessitated. The last or thirteenth line, scoring for the player the arbitrary number "40," may of course be completed by any one of the seven dominoes running from double blank to six-one in diagonal sequence.

It is to be understood that there is no prescribed order in which any of the lines are to be completed, such order of completion being entirely dependent upon the caprice or whim of the various players and their judgment as to the possible dominoes held in the hands of their opponents. It is to be remembered also that there is a place for every domino and that each domino should be in its play put in its proper position above the like domino painted, printed, or otherwise affixed to the board B, the three corner plays, double blank, blank-one, and six-one, being the only arbitrary plays allowed.

It may occur during the progress of the game that some player cannot play, in which event I have deemed it advisable that one of the other players should draw a domino from the hand of the one unable to play and place the same upon the board, spots up, to be played in its place as soon as the game has progressed far enough. All dominoes placed spots up upon the smooth part of the board become the common property of all of the players, and it is the duty of all alike to watch closely the progress of the game, so that these exposed dominoes may be played at the first opportunity, it being required, as before, that these dominoes, like those regularly played, shall only be played in their proper sequence 130 or proper position; but should the playing of any such exposed domino finish a line or fill a corner it does not count for any player. After all of the dominoes have been placed in

position and the triangle completed they are shuffled as before and the game proceeds in the same manner until some one of the players makes a total score of four hundred.

5 Although I have specifically defined the manner in which I prefer to play the game, I do not limit myself to any special set of rules, as it is apparent that many modifications of the rules hereinbefore indicated may be adopted and still come within the scope of my invention. Nor do I limit myself to any especial type of device or apparatus for effecting the result attained, as it is obvious that the same result might be attained with the use 10 of ordinary dice by arranging them in the grooves with the spots of the various denominations up or exposed in the same manner as are the dominoes; or, in fact, a game of similar character might be arranged with common 15 playing-cards, giving to each individual type of card—as the king, for instance—a definite valuation, the essence of my invention lying in the arrangement of rows of movable parts, having displayed upon some part of each a 20 definite valuation, so that when said rows are completed in a predetermined sequence the summation of the valuations are counted 25 or appropriated to the count of the player completing such row or rows.

30 Having thus described my invention, what I claim, and desire to secure by Letters Patent of the United States, is—

1. A game consisting of a board provided with rows of parts having each a definite numerical value or indication and permanently arranged in a predetermined sequence, in 35 combination with movable parts having like individual valuations or characters and adapt-

ed to be placed upon said fixed rows of parts in a prearranged order, substantially as described. 40

2. A game consisting of a board or base having rows of parts of definite valuation or indication permanently affixed thereto and arranged in a predetermined sequence, in combination with movable parts of like valuation or character adapted to be arranged over said fixed parts in a definite or prearranged order, said fixed rows or parts having summation values which count for the player when the 45 movable parts are placed upon the fixed parts in the definite or prearranged order, substantially as described. 50

3. A game consisting of a board or base B having painted or otherwise affixed to the 55 surface thereof a set of dominoes in a definite order, in combination with a movable set of dominoes adapted to be placed over the fixed dominoes in the same order, substantially as described. 60

4. A game consisting of a board or base B having strips or grooves which divide it into rows, in combination with dominoes painted or otherwise affixed thereto in definite sequence between said strips or grooves, and 65 movable dominoes adapted to be placed over the fixed dominoes in a definite or prearranged order, substantially as described.

In testimony whereof I have hereunto subscribed my name this 7th day of November, 70 1898.
